(57) **CLAIM**

The ornamental design for portable integrated firewood stove with oven, substantially as shown and described.

DESCRIPTION

FIG. 1 is a front perspective view of portable integrated firewood stove with oven, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The oblique shading lines in the drawings denote the transparency of surface planes on the portable integrated firewood stove with oven.

The broken lines and areas within depict portions of the portable integrated firewood stove with oven that form no part of the claimed design.
